(57) CLAIM

I claim the ornamental design for a fabric with pattern, as shown and described.

DESCRIPTION

FIG. 1 is a top plan view of a first embodiment of a fabric with pattern, showing the repetitive unit of my new design; FIG. 2 is a top plan view of a second embodiment thereof; FIG. 3 is a top plan view of a third embodiment thereof; and, FIG. 4 is a top plan view of a fourth embodiment thereof.

1 Claim, 2 Drawing Sheets

FIG. 1

FIG. 2

FIG. 4
